UNITED STATES PATENT OFFICE.

LARS H. EKEBERG, OF ROCKFORD, ILLINOIS.

SIGNAL FOR VEHICLES.

Application filed April 17, 1922. Serial No. 553,770.

To all whom it may concern:

Be it known that I, LARS H. EKEBERG, a citizen of the United States, residing at Rockford, in the county of Winnebago and 5 State of Illinois, have invented certain new and useful Improvements in Signals for Vehicles, of which the following is a specification.

This invention pertains to signal devices 10 especially adapted for use on motor vehicles to indicate stop, turn, etc., and the primary object is to provide an improved signal of this character.

Another object is to provide a signal constructed in such simple and novel manner 15 that it may be economically produced at a low cost and will be adapted for convenient application to different makes of motor vehicles at any of various positions at which 20 the signal may be effectively displayed.

More particularly, I have aimed to provide a device of the character described embodying a simple and novel signal element 25 consisting of a plurality of fingers adapted to gravitate from a collapsed, concealed position to a display position simulating an open hand, said fingers being movable to and from said signal position at the will of the operator.

30 I have also aimed to embody one or more signal elements of this character in a supporting frame of tubular form, at the ends of which are carried electric bulbs, and to provide an electric circuit and operating 35 means whereby the signal element may be projected from either end of the tubular supporting member and lighted when the signal is displayed.

Other objects and attendant advantages 40 will be appreciated by those familiar with this art as the invention becomes better understood by reference to the following description when considered in connection with the accompanying drawings, in 45 which—

Figure 1 is a front view of a motor vehicle showing the application thereto of a signal device embodying my invention;

Fig. 2 is a view looking at the rear of the 50 device, detached, and showing the means for operating the signal;

Fig. 3 is a longitudinal sectional view 55 through the signal device in its position shown in Fig. 2;

Fig. 4 is a detail section taken on the line 3—3 of Fig. 2;

Fig. 5 is a top view of an electric connector on the tubular supporting member;

Fig. 6 is a sectional view taken on the line 6—6 of Fig. 5; and

Figs. 7 and 8 are diagrammatic views illustrating the electric circuit which will be explained hereinafter.

My improved signal device may as mentioned above, be applied in any suitable 65 manner and at any location on a motor vehicle for effectively displaying the signal. In the preferred embodiment a signal may be displayed at either side of the vehicle as a warning to those following that the driver 70 intends to turn to the side indicated, or to stop. In the present case, the device is applied as shown in Fig. 1, just below the auto top and at the rear of the windshield. This, however, is simply for purpose of illustration and is no way a limitation as to location 75 of the device.

In the present instance the device consists of a tubular supporting member or holder 11 adapted to be fixedly attached by any 80 suitable means to a motor vehicle, as for example in the position shown in Fig. 1, in which said member reaches from side to side of the vehicle. Within said member, there is axially slidable, a rod designated 85 generally by 12, in each end of which is carried a signal element or device consisting of a plurality of fingers 13 pivotally mounted at 14 on the rod. The rod 12 is substantially of the same length as its supporting member 11 and may be moved axially in either direction to project either end beyond said member. For this purpose, any suitable or preferred means may be employed, such for example as a manually operable knob 95 15 attached to the rod 12 by means passing through a slot 16 in the member 11. Other means may be employed for reciprocating the rod 12, as for example, a cable 17 run through guides 18 arranged as shown 100 in Fig. 2 and connected to the knob 15. This cable is crossed as shown and equipped on its lower horizontal reach 19 with a knob 21 adapted to be moved to the left and right by hand for correspondingly shifting the 105 rod 12. When this rod is shifted to sufficiently project either end from the holder 11, the fingers 13 which are normally disposed within the rod 12 and rest on the bottom interior wall of the holder, will drop 110 to the display position shown at the left hand end of Figs. 2 and 3. The fingers

2

are limited in their pivotal movement by abutment of their inner ends 22 against the overhead surface on the rod, the inner ends 22 of the fingers being so shaped that they 5 will be limited to positions in separated relation so as to simulate an open hand. The face of each finger is painted to produce black and white sections with the black sections of each finger in staggered relation 10 with those of the next adjoining finger. The result is a very effective signal display as plainly shown in the drawing. It will be manifest that the fingers will be moved to a collapsed position within the rod 12 by 15 movement of the rod to its inner position, it being noted that the underside of the rod beneath the fingers is open to allow free passage of the fingers from one position to another.

20 In each end of the rod I have provided an electric light socket for a light bulb 23 which is directed toward its adjacent signal element for illuminating the same. The light bulbs are grounded on the metallic 25 end portions of the rod 12, which in turn are grounded through the holder 11 on the car frame, and each bulb is connected by a wire 24 to a contact plate 25 fixed to the top of the rod, as shown in Figs. 7 and 8.

30 It will be observed that the rod 12 is of sectional construction, consisting of a center section 26, which may be of any non-conducting material, such as wood or fibre, and metallic end sections 27 telescoping and fixed 35 to the center section. It is to this center section that the contact plates 25 are attached and thus insulated from the end sections of the rod. Either light circuit is adapted to be closed by a contact maker 28 connected 40 to the source of current. This contact maker is at present in the form of a spring element carried on the holder 11 by means

of an insulation plate 29 held in position by the tabs 31 as shown plainly in Figs. 5 and 6. It will be manifest that when the 45 rod is moved to either signal position, one of the plates 25 will be brought into contact with the terminal or contact maker 28, thereby closing the light circuit and illuminating the signal being displayed.

50 It is believed that the foregoing conveys a clear understanding of the objects pre-faced above, and while I have illustrated but a single working embodiment it should be understood that considerable change 55 might be made in details of construction without departing from the spirit and scope of the invention as expressed in the appended claim.

60 I claim:

A signal for vehicles comprising a tubular holder adapted to be attached to a vehicle reaching from side to side thereof, a signal carrying rod slidably in said holder and having a center section and end sections and being of approximately the same length as said holder, each end section being tubular and open on its underside, a signal device disposed in the open portion of each end section comprising a plurality of fingers pivoted 70 at their inner ends to the outer end of the center section and having inner ends of different lengths serving as stops for limiting the signal position of the respective fingers, and means for moving said rod lengthwise 75 in the holder to project either end therefrom, the fingers of each signal device being normally confined within and resting on the bottom of the holder and adapted when projected to drop at their outer ends to the 80 signal position through the open underside of the projected rod section.

LARS H. EKEBERG.
